KEY DUPLICATING DEVICE

Application filed June 18, 1930. Serial No. 462,057.

This invention relates to a key cutting device and more particularly to a device constituting a gauge and by means of which a blank key may be accurately cut in order to provide a determined pattern so that it will fit a lock having tumblers of a determined character.

At the present time keys for locks of the Yale type are numbered and the locks similarly numbered for identification purposes. The numerals of the numbers indicate the character of the notches formed in the edge of the key and one object of the invention is to provide a device including a key holder and a gauge movable through the holder and marked with numerals whereby the gauge may be accurately set and a blank key cut to form a notched edge of a desired pattern. By this arrangement a new key can be easily made as it is only necessary to read the numbers upon a lock and successively set the gauge according to the numerals of the number while filing the new key.

Another object of the invention is to so form the key cutting device that the key and gauge holder may be secured in a vice of a conventional construction thereby eliminating use of expensive machinery.

Another object of the invention is to provide a device of this character which is very simple in construction, consists of a few number of parts and can be very easily operated.

This invention is illustrated in the accompanying drawings, wherein:

Figure 1 is a perspective view showing the improved key cutter in use.

Figure 2 is an enlarged view of the gauge shown in use in Figure 1.

Figure 3 is a view of a gauge somewhat similar to the gauge shown in Figure 2 but of a modified construction.

Figure 4 is a view showing another modified form of gauge applied to the key and gauge holder.

Figure 5 is a view of the gauge shown in Figure 4.

Figure 6 is a fragmentary sectional view

through the block or body portion of the key cutter.

The improved key cutting device constituting the subject matter of this invention consists of a block or body 1 which may be referred to as a key and gauge holder together with a gauge which may be constructed as shown in Figures 2, 3 and 5. These gauges are indicated respectively by the numerals 2, 3 and 4. It is to be understood that these represent types of gauges which may be used in connection with the block and that others may be found suitable for use therewith.

The block 1 is formed of strong metal and has its lower portion reduced in thickness from its front face thereby forming a shank 5 adapted to be gripped between jaws 6 of a vice 7 and a shoulder 8 to rest upon one jaw as shown in Figure 4 and cause the block to be held in its proper position. Slots 9 and 10 are cut in the block from its upper face at right angles to each other and it should be noted that the slot 9 is deeper than the slot 10 and has its upper end enlarged as shown at 11 to form a mouth having bevelled side walls serving to limit the distance a file may enter the slot and also serving to guide the file and cause notches to be cut at a proper angle so in an edge of a key 12 when the key is fitted into the slot 10 as shown in Figures 1 and 4 with its lower edge resting upon the gauge.

An opening 13 is formed through the block below and parallel to the slot 10 and in spaced relation to one side of the opening 13 are formed upper and lower openings 14 and 15. The opening 13 receives a pin 16 while either of the openings 14 and 15 may receive a pin 17 carried by a resilient strip 18. This strip 18 serving as a mounting for the pin 17 extends vertically along a side face of the block and is formed with a slot 19 through which passes the threaded shank 20 of a thumb screw 21. This thumb screw enters a threaded opening 22 formed in the block and it will be readily understood that by tightening the thumb screw the resilient strip may be secured and the pin 17 retained in the selected opening 14 or 15. Since the

- strip is resilient the pin may be drawn outwardly sufficient to clear the slot 9 and permit a gauge to be set in place, adjusted or removed. A metal washer 22' and a felt washer 23 are provided between the resilient strip and side face of the block so that when the screw is tightened the resilient strip will be firmly held in place and the screw prevented from working loose.
- 10 The gauge 2 illustrated in Figure 2 consists of a metal strip of a thickness to be received in the slot 9 and this strip tapers towards one end so that as it is moved longitudinally through the slot the distance between its upper edge and the top of the slot varies. Therefore, when a key is placed in the slot 10 and the gauge strip moved the key will be raised or lowered according to the direction in which the gauge is moved
- 15 and a deep or shallow notch may be cut by a file reciprocated in the mouth of the slot 9 until cutting is stopped by engagement of the file with the bevelled faces 11. Openings 24 designated by numerals 1 through 9 are formed through the gauge strip and arranged in rows as shown so that when the gauge is moved through the block the openings of the lower row will successively register with the opening 13 while the openings of the upper row will register with the opening 14. By noting the number upon a lock and moving the gauge through the block until the opening designated by the first numeral of the number registers with its cooperating opening in the block the pin 16 can be passed through the registering openings. The key will then be supported at such a height that the first notch can be properly filed. After the first notch has been cut the pin is removed and the gauge slid longitudinally until its opening having a numeral corresponding to the second numeral of the lock number registers with its cooperating block opening and the pin again inserted. Movement of the gauge raises or lowers the key and the second notch can be accurately cut. This is repeated until all the necessary notches have been cut thereby producing a key which will fit the lock. Therefore, it is not necessary to remove a lock from a door and take it to a locksmith in order to obtain a new key, it being merely necessary to supply the locksmith with the number in order to permit him to make a new key.
- 20 The gauge 3 illustrated in Figure 3 is somewhat similar to that of Figure 2 and consists of a strip of metal tapered towards one end and formed with a longitudinally extending slot 25 cut parallel to one side edge of the strip. Notches 26 and 27 designated by numerals 1 through 9 are formed in side edges of the strip and it should be noted that the notches 26 increase in depth towards
- 25 the narrow end of the strip whereas the

notches 27 increase in depth towards the wide end of the strip. When this gauge is used it is set into the slot 9 and the pin 16 passed inwardly through the opening 13 and through the slot 25. Therefore, the gauge may be slid longitudinally until the desired notch registers with the slot 10 and the key set in place with its lower edge resting in the notch of the gauge and a notch filed in the upper edge of the key. The key by engaging in a notch of the gauge holds the gauge in a set position and it is necessary to raise the key in order to shift the gauge before filing another notch in the key.

30 In Figure 4 the gauge 4 illustrated in Figure 5 has been shown in use. This gauge consists of a circular disk having an eccentrically located opening 28 formed therein to receive the pin 16 when the gauge is set in place with the opening registering with the opening 13 of the block. Openings 29 designated by numerals 1 through 9 and arranged in inner and outer arcuate rows concentric to the disk are formed in spaced relation to the periphery of the disk and these openings register with the openings 14 and 15 of the block as the disk is turned about the pin 16. By withdrawing the pin 17 and shifting the strip 18 after loosening the screw 21 the pin may be inserted in a selected opening 14 or 15 and through an opening 29 in order to secure the gauge in a set position while filing a notch in a key and the gauge then released and shifted to raise or lower the key so that another notch may be properly filed therein. The key rests upon the marginal edge of the gauge disk when placed in the slot 10 and since the disk is eccentrically mounted a cam action serving to vertically adjust the key takes place when the disk is turned about the pin 16.

35 While we have particularly described the elements best adapted to perform the functions set forth, it is obvious that various changes in form, proportion and in the minor details of construction may be resorted to without departing from the spirit of the invention or the scope of the appended claims.

40 Having described our invention, what we claim is:

1. A key cutting device comprising a body formed with a key seat opening through the top thereof, a gauge movable through said body in crossed relation to the key seat and extending through the key seat and adapted to support a key with an edge portion projecting upwardly from the body, and means to releasably secure the gauge in a set position with a predetermined portion of the key projecting from the body whereby notches of desired depth may be cut in the exposed edge of the key.
2. A key cutting device comprising a body

formed with a key seat opening through the top thereof, a gauge movable through said body transversely of the key seat and having a sloping upper edge to engage a key and support a key with an edge portion projecting from the body a determined distance according to the position occupied by the gauge, and a pin slidable through the body into and out of position to engage the gauge and releasably secure the same in set positions whereby notches of desired depth may be cut in the exposed edge of the key.

3. A key cutting device comprising a body formed with a key seat, a gauge movable through said body transversely of the seat and extending through the seat and having a sloping edge face to engage a key and support a key with an edge portion projecting from the body a determined distance according to the position occupied by the gauge, a pin slidable through the body into and out of position to engage the gauge and releasably secure the same in set positions with an edge portion of the key to be filed projecting from the body desired distances, and a resilient strip to yieldably retain the pin in an operative position connected to the outer end of said pin and secured to said body.

30 4. A key cutting device comprising a body formed with gauge and key receiving seats extending in crossed relation to each other, a gauge movable through the gauge receiving seat whereby a key disposed in the key receiving seat and resting upon the gauge may be supported with an edge portion to be cut projecting from the key seat determined distances from the body, the body having openings formed therein and the gauge having openings to be selectively registered with the openings of the body as the gauge is moved to adjust the distance the edge portion of a key to be cut projects from the body, and a pin engageable through the openings of the body and key to releasably secure the gauge in a set position.

5. A key cutter comprising a body, said body being formed with gauge and key receiving seats extending in crossed relation to each other, a gauge movable through the gauge receiving seat whereby a key disposed in the key receiving seat and resting upon the gauge may be supported with an edge portion to be cut projecting determined distances from the body and means to releasably secure said gauge in a set position.

6. A key cutter comprising a body, said body being formed with gauge and key receiving seats extending in crossed relation to each other, and a gauge movable through the gauge receiving seat and adapted to support a key in the key receiving seat with an edge of the key to be cut projecting from

the body determined distances whereby a series of notches of desired depth may be cut in the exposed edge of the key.

7. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge movable in the gauge receiving slot and adapted to engage the lower edge of a key disposed in the key receiving slot and support the key with a determined portion projecting upwardly above the body and a pin passed through one of the openings of the body and through the gauge to secure the gauge in place.

8. A key cutter comprising a body, the upper portion of said body being cut from its upper end face to form slots extending in crossed and intersecting relation to each other, one slot constituting a key receiving seat and the other being deeper and constituting a gauge receiving slot and a gauge movable through the gauge receiving slot and adapted to engage the lower edge of a key disposed in the key receiving slot and support the key with its upper edge projecting above the body determined distances whereby notches of desired depth may be cut in the key.

9. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge slidable through the gauge receiving slot and formed with openings to register with openings of the body, and a pin passed through registering openings of the body and gauge to secure the gauge in position to support the key with its upper edge projecting above the body determined distances whereby notches of desired depth may be cut in the key.

10. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge slidable through the gauge receiving slot and formed with openings to register with openings of the body, a screw threaded into said body, a resilient strip

formed with a longitudinally extending slot receiving said screw whereby the strip may be secured in a set position and a pin fixed to one end of said strip and slidably received in a selected opening of the body and engageable through a selected opening in the gauge whereby the gauge may be releasably secured in a set position and support a key with its upper edge to be cut 10 projecting from the body a desired distance.

11. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge slidable through the gauge receiving slot and formed with notches in its edges to register with the key receiving slot and cause the upper edge of a key to be cut to project from the body 20 determined distances whereby notches of desired depth may be cut in the key, a longitudinally extending slot being formed in the gauge, and a pin passed through the body and through the slot of the gauge to 25 retain the gauge in place and guide and limit movement of the gauge.

12. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge disk in the gauge slot having an eccentric opening registering with one opening of the body, a pin passed through the registering openings to pivotally mount the disk whereby a key may be supported in its slot with the upper edge of the key projecting from the body determined distances while being filed to form notches and means to releasably secure the gauge disk in set positions.

13. A key cutter comprising a body, the upper portion of said body being cut from its upper end face to form slots extending in crossed and intersecting relation to each other, one slot constituting a key receiving seat and the other being deeper and constituting a gauge receiving slot, openings being formed through said body in cross and intersecting relation to the gauge receiving slot, a gauge disk in the gauge slot having an eccentric opening registering with one opening of the body, a pin passed through the registering openings to pivotally mount the disk whereby a key may be supported in its slot with the upper edge

of the key projecting from the body determined distances while being filed to form notches, other openings being formed in the disk and spaced from each other along arcuate lines concentric to the disk the last mentioned openings of the disk being adapted to successively register with another opening of the body as the disk is turned about its pivot pin, and a pin to engage through the last mentioned registering openings of the gauge disk and body and releasably secure the disk in set positions.

In testimony whereof we affix our signatures.
